UNITED STATES PATENT OFFICE.

HUBERT A. DOTY, OF BOSTON, MASSACHUSETTS.

ARTIFICIAL LIMB.

1,134,185.

Specification of Letters Patent.

Patented Apr. 6, 1915.

Application filed May 22, 1914. Serial No. 840,375.

To all whom it may concern:

Be it known that I, HUBERT A. DOTY, a citizen of the United States, residing at Boston, in the county of Suffolk and State 5 of Massachusetts, have invented new and useful Improvements in Artificial Limbs, of which the following is a specification.

This invention relates to improvements in artificial limbs and has for its object to 10 provide a limb having two sections pivotally connected together, one of said sections constituting a stump socket which is arranged to slide on metallic guides, said stump socket being yieldingly supported by 15 springs arranged in and protected by metallic casings.

The invention consists in the combination and arrangement of parts whereby the above objects and certain other objects hereinafter appearing may be attained, as set 20 forth in the following specification and particularly pointed out in the claims.

Referring to the drawings: Figure 1 is a side elevation of a portion of an artificial 25 limb embodying my invention, parts of said limb being broken away to save space in the drawings and to more clearly illustrate the same. Fig. 2 is a section, partly in elevation, taken on the line 2—2 of Fig. 1. Fig. 30 3 is a transverse section taken on the line 3—3 of Fig. 1, parts of the socket being broken away to save space in the drawings.

Like numerals refer to like parts throughout the several views of the drawings.

35 In the drawings, 5 is the lower or shank member and 6 the upper member or corset which is pivotally connected to the member 5 by hinge members 7 and 8 arranged upon opposite sides of said upper and lower members. Each of the hinge members 7 and 8 is formed in two parts 9 and 10, the part 9 of 40 said members being secured preferably by rivets 11 to the lower or shank member 5, while the member 10 is detachably arranged 45 in leather sockets 12 stitched to opposite sides of the corset 6.

The members 9 and 10 are pivotally connected together at a point substantially coinciding with the axis of the knee joint of 50 the wearer.

The most important feature of the invention resides in the supporting guiding means for the stump socket 32, said stump socket being of the well known slip socket 55 type, the same being arranged to slide vertically in the upper end of the shank mem-

ber 5 and having the usual rubber cushion 33 at the bottom thereof which is arranged to engage the upper edge of the member 5 when said socket is depressed to its full 60 extent.

A metallic band 34 is secured to the upper edge of the member 5 surrounding the gap which is normally maintained between the cushion 33 and the upper edge of said member 5. The stump socket 32 is arranged intermediate the parts 9 of the hinge members 7 and 8, said parts 9 extending for a substantial distance above the shank portion 5 to which they are secured, as hereinbefore 70 stated, by rivets 11.

To afford a more rigid support for the hinge members, the parts 9 are provided with projections or lugs 35 which extend laterally from opposite sides of said members and engage said member 5 adjacent the upper end thereof. From the lugs 35 upwardly substantially to the joint or pivoted point for said hinge members, said members 9 are substantially straight. Said 80 straight portions are arranged to reciprocate in guide plates 36 preferably formed of aluminum and having grooves 36' extending longitudinally thereof and provided with linings 37 of relatively softer 85 material preferably leather, said guide plates being secured to the socket 32 preferably by screws 38.

The supporting means hereinbefore referred to preferably consist of springs 39 interposed between the socket 32 and the member 5, but directly engaging the guide plates 36 and means supported upon the member 9, said means preferably consisting of pins 40, one of which is secured to each of the members 9 on lugs 41 projecting inwardly from 90 said members. The upper ends 42 of the pins are substantially smaller in diameter than are the lower portions thereof, thus providing shoulders 43 against which the 95 lower ends of the springs 39 rest.

A spring tube 44 surrounds each of the springs 39, said tube being closed at its upper end, while its lower end is adapted to engage the larger portion of the pin 40 and 100 to slide longitudinally thereof, said tube being arranged in grooves 45 and 46 formed in the members 9 and 36 respectively.

The upper ends of the tubes 44 are preferably rounded and adapted to fit correspondingly shaped depressions 47 formed in the guide plates 36, said depressions serving 110

to prevent displacement of the tubes. It will be evident by this construction that the springs 39, which are arranged at opposite sides of the socket 32, will at all times be entirely inclosed and guided within their respective spring tubes, thus preventing dirt or foreign substances from collecting therein.

Heretofore the stump sockets adapted to fit artificial limbs of the nature hereinbefore described have been provided with guides constructed of wood and covered with leather which engage the hinge members to control the vertical movements of said sockets. This has led to a great deal of annoyance to the wearer of the limb owing to the expansion of the socket, due to the pressure of the stump therein, said expansion causing the separation of the guides which, as hereinbefore stated, control the vertical reciprocations of said stump socket, thus causing the same to rattle against the hinge members. This annoyance has been overcome in the present case by providing the metal guide plates 36 which extend substantially around the members 9 and lining the recesses within which said members 9 are located with leather.

While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts, nor to its specific application herein shown, but that extensive deviations from the illustrated form or embodiment of the invention may be made without departing from the principles thereof.

Having thus described my invention what I claim and desire by Letters Patent to secure is:

1. An artificial limb having, in combination, an upper member, a lower member, hinge members connecting said upper and lower members at opposite sides, a stump socket arranged to slide in said lower member intermediate said hinge members, metal guides on said socket adapted to engage said hinge members to guide said socket during its sliding movements in said lower member, a guide pin on each of said hinge members, a spring encircling each of said pins, and a spring tube surrounding each of said springs and having engagement with the adjacent metal guide.

2. An artificial limb having, in combina-

tion, a lower member, a pair of hinge members secured at opposite sides of said lower member, a stump socket arranged to slide between said hinge members, metal guide plates secured to said stump socket, said guide plates having grooves adapted to receive said hinge members, and springs arranged between said guide plates and said hinge member and concealed thereby, said springs adapted to yieldingly support said stump socket relatively to said lower member.

3. An artificial limb having, in combination, a lower member, a pair of hinge members secured at opposite sides of said lower member, a stump socket arranged to slide between said hinge members, metal guide plates secured to said stump socket, said guide plates having grooves adapted to receive said hinge members, and a lining for said grooves adapted to deaden the sound produced by the movements of said socket relatively to said lower member.

4. An artificial limb having, in combination, a lower member, a pair of hinge members secured to said lower member, a stump socket arranged to slide relatively to said lower member and intermediate said hinge members, guide plates secured to said stump socket, said plates having grooves adapted to receive said hinge members, a pin arranged longitudinally of each of said hinge members, a spring adapted to encircle each of said pins, a tube inclosing each of said springs and having sliding engagement with said pin, and projections on said plates adapted to engage the ends of said tubes.

5. An artificial limb having, in combination, a lower member, a pair of hinge members secured to said lower member, a stump socket arranged to slide relatively to said lower member and intermediate said hinge members, guide plates secured to said stump socket, said plates having grooves adapted to receive said hinge members, the adjacent faces of each of said plates and their adjacent hinge members being oppositely grooved, and a spring interposed in each of said grooves, between said plate and said hinge member respectively.

In testimony whereof I have hereunto set my hand in presence of two subscribing witnesses.

HUBERT A. DOTY.
